UNITED STATES PATENT OFFICE.

HERBERT W. OWEN, OF DOVER, NEW HAMPSHIRE.

SPINNING OR WINDING MACHINE.

1,119,530.

Specification of Letters Patent.

Patented Dec. 1, 1914.

Application filed January 21, 1913. Serial No. 743,294.

To all whom it may concern:

Be it known that I, HERBERT W. OWEN, a citizen of the United States, and resident of Dover, county of Strafford, and State of New Hampshire, have invented an Improvement in Spinning or Winding Machines, of which the following description, in connection with the accompanying drawings, is a specification, like letters on the drawings representing like parts.

The invention to be hereinafter described relates to spinning or winding machines, wherein yarn is wound upon the bobbins for subsequent use.

As well understood by those skilled in the art, where the yarn is to be subsequently used as filling, the bobbin is wound in conical layers, and both the base and tip portions of the wound mass present substantially similar conical forms. It is desirable to increase the amount of yarn on filling wound bobbins by reason of the economy incident thereto, the less number of replenishments necessary in the loom during weaving, and other advantages readily appreciated by those familiar with the art. In the case of bobbins for use in some types of looms, known generally as filling replenishing looms, bunches of yarn have been preliminarily wound on the appropriate part of the bobbin to coact with mechanism on the loom, but the formation of such bunches has introduced special and complicated mechanism in addition to the usual builder motion which is, of course, objectionable.

In a prior application, Serial No. 661,798, filed November 22, 1911, there was shown, described, and broadly claimed, means whereby an increased amount of yarn could be wound upon the bobbin while still maintaining the characteristics of the filling wind. The said means was broadly characterized by automatically causing the traverse of the builder motion to be shortened while winding the yarn at the base portion of the bobbin and then gradually lengthened as the yarn was wound in successive layers at the portions of the bobbin above the base until the normal traverse of the builder motion was reached, which was then continued to the tip of the bobbin. While the invention in said prior application was generally set forth and claimed, as above outlined, the particular embodiment of the invention as shown by the drawings of said application, involved the principle of the

movable pulley. I have found, however, that a greater variation in the character of the bunch may be secured and a wider range of adjustments and advantages obtained by modifying the action of the movable pulley, and while the present invention aims to secure these further desirable conditions, it is yet subordinate to the broad invention as disclosed in said prior application.

The aims and purposes of the present invention will best be made clear by the following description and accompanying drawings of one form or embodiment of means for carrying it into practical effect, it being understood that said means may be varied within the true scope of the invention which is definitely pointed out by the claims.

In the drawings:—Figure 1 represents in front view sufficient portions of a ring spinning frame provided with the present invention to make clear its construction, use, and purposes; Fig. 2 is a side view of one form of builder motion that may be conveniently employed to impart the usual traverse movements to the ring-rail; Fig. 3 is a side elevation of the base portion of a bobbin showing by full and dotted lines different characters of wound bunches; Fig. 4 is a side view of a filling wound bobbin which may be produced by the use of the present invention; and Fig. 5 is a modification, showing the eccentrically mounted member formed as a cam.

In the drawings, the invention has been shown as applied to a ring spinning frame which may be of any usual or preferred character, wherein the spindle rail 1 sustained by suitable supporting means may have mounted thereon a series of spindle bearings 2 for holding a series of spindles 3, on which the yarn is to be wound. Obviously the spindle bearings may be of any desired character, and the spindles themselves, only one of which, however, is shown by the drawings, may be rotated by any suitable means. The ring-rail 4, which may be provided as usual with a series of rings 5 each having a traveler 6, is supported upon the usual lifter rods 7, only one of which is indicated, and these in turn are associated with suitable rockers or levers, 8 having a weight 9 whereby the ring-rail is elevated or given its rising movements. Projecting from the rocker 8 is the rocker arm 10 having connected to its upper end a link 11 extend-

ing to another rocker arm which is a duplicate of that described and associated with another lifter rod. The parts so far described are or may be of any usual character and being well understood by those skilled in the art, need not be further described.

The rocker arm 10 is provided with the usual segment 12 to which is secured the support or yoke 13 by means of the connection 14. Said connection 14 may be of any suitable character but is preferably formed as a chain, and may be adjustable in length as by means of the thread portion 15 and adjusting nuts 16.

15 Mounted eccentrically at 17 in the support or yoke 13 is the movable member 18, preferably provided with teeth 19. This movable member 18 may be variously formed, the essential in this respect, so far as the 20 present invention is concerned, being that it may engage the connection to the builder motion at opposite sides of its fulcrum 17 and at varying distances therefrom, as will hereinafter more fully appear.

25 The builder motion is best illustrated in Fig. 2, and may be of any usual or well understood type. As shown it comprises the builder arm 20 having a weight 21 and carrying a roll 22 which is actuated by the 30 traverse cam 23. Pivoted at 24 to the builder arm 20 is the lever 25, the end of which is connected to the chain or other flexible member 27. The lever 25 is provided with a curved bearing surface 28 for 35 the roll 29 carried by the slide 30, said slide having teeth 31 operatively engaged by the worm 32 on the shaft 33. The shaft 33 has the pick wheel 34 actuated by the pawl 35, the construction being such that as the 40 traverse cam 23 gives uniform movement to the builder arm 20, the lever 25 will partake of said uniform movement but will transmit such movement in different paths, as usual. Since the particulars of the builder motion 45 are well understood by those skilled in the art, further description thereof will be unnecessary.

The chain, or other connection 27 leading to the builder motion, passes upward, as indicated in Fig. 1, and over suitable guiding devices 36, beyond which it is joined by a swivel 37 to a flexible loop 38. This loop, as indicated by Fig. 1, embraces the eccentric member 18 and is preferably formed as 55 a sprocket chain, the links of which are adapted to engage the teeth 19 of the eccentric member 18, and one run or member of said loop is elastic. As a convenient formation, the elastic portion of the loop 60 is formed by a spring 39, one end of which is secured to the main portion of the loop, as at 40, while the other is connected to the end of the chain portion of the loop at 41, the construction being such that, as the 65 builder motion draws upon the rocker arm

and force moves the eccentric member to the left, in Fig. 1, if the end portion 41 of the spring is restrained from such movement, the non-yielding portion of the loop will cause the eccentric member 18 to turn 70 upon its eccentrically-arranged fulcrum and force impart to the rocker arm and consequently to the ring-rail a movement less than the full traverse of the builder motion, as will more fully appear. As one means to 75 this end the elastic portion 39 of the loop is connected to an arrester or stop device, which acts during the formation of the bunch portion of the wind as the builder motion draws the rocker arm in the direction to lower the ring-rail. The particular means employed for this purpose may obviously be varied, but a good practical and convenient form thereof is shown in Fig. 1, wherein the elastic portion of the loop is 80 joined to the machine frame by a connection 42. This connection 42 is preferably made flexible and, as shown, is formed as a chain having one end attached to the elastic portion of the loop at 41, and the other end 85 adjustably secured to a bracket 43 by a threaded rod 44 and adjusting nuts 45, the length of said connection being such that during the building of the bunch at the base portion of the bobbin, as the rocker arm 90 is drawn to the left, Fig. 1, the connection 42 will arrest the movement of the lower run of the chain loop 38, whereupon the upper run of the chain loop will act to turn the eccentric member 18 on its fulcrum and 95 simultaneously move it bodily to the left. Thus the eccentric member 18 is caused to act both as a movable pulley and as an eccentric or lever, imparting to the ring-rail a differential traverse movement partaking 100 of the character of both. As the bunch is gradually built up, the builder motion draws the rocker arm less and less distance to the left, Fig. 1, so that the arrester or stop device 42, acts less and less until finally 105 it ceases to act entirely and remains slack, whereupon the full traverse of the builder motion is imparted to the ring-rail which continues to the top of the bobbin.

It will be evident that before the machine 110 is set in motion, the eccentric member 18 may be adjusted about its pivot or fulcrum 17 by disengaging the loop from the teeth thereof, and that by reason of its eccentric mounting the leverage on opposite sides of the pivot or fulcrum may be varied with consequent variation in the form or character of the bunch. Indeed, by proper formation of the eccentric member and its adjustment, as indicated, the bunch may be given 115 an almost unlimited range of formation, as indicated by Fig. 3, wherein the bobbin *a* is shown by full and dotted lines as being provided with bunches *b* or *c* of widely 120 different characters. These and any forms 125

intermediate the two are possible and within the range of the invention.

In Fig. 4, a full bobbin wound by the invention described is shown, and it will be noted that while it is characterized by the filling or conical wound body and tip portions *d* and *e* respectively, the base portion *f* is full and rounded.

In Fig. 5 the eccentric member is shown somewhat modified in form, and as comprising an eccentrically mounted cam 46 mounted to turn upon its fulcrum 17. This and other modifications of the eccentric member will readily suggest themselves to those skilled in the art according to the character and form of the bunch desired to be placed upon the bobbin, all of which modifications, however, are clearly within the scope of the present invention as defined by the claims.

It will be noted in Fig. 1 that the arrester or part 42 passes through a slot 47 in the rocker arm 10, shown by dotted lines, so that the upper edge portion 48 thereof may act on the part 42 like a nose or foot as the rocker arm turns contra-clockwise, Fig. 1, to thereby bend the part 42 downward and augment its action on the extensible portion of the loop and cause increased turning movement of the eccentric member 18. This, however, while of importance in some cases, may not always be necessary.

What is claimed is:—

1. In a machine of the character described, the combination of a builder motion and traverse mechanism, flexible connections between said builder motion and traverse mechanism, said flexible connection having a closed loop, an eccentric member engaging the loop of said flexible connections, and means for varying the length of the loop to vary the traverse of the traverse mechanism during the building of a bunch.

2. In a machine of the character described, a series of spindles, a traversing mechanism, and a builder motion, permanent operable flexible connections including an extensible portion between the builder motion and said traversing mechanism, an eccentric member engaging said connections, and means for varying the length of the extensible portion of said connections to impart a variable traverse to the traversing mechanism during the building of a bunch.

3. In a machine of the character described, a series of spindles, a series of guides, a traversing mechanism for said guides, a builder motion, extensible transmitting connections between the builder motion and traversing mechanism including an eccentric member, and an arrester or stop acting on said connections during the building of a bunch to turn the eccentric member upon its fulcrum and elongate said extensible connections.

4. In a machine of the character de-

scribed, the combination of a builder motion and traversing mechanism, connections between said builder motion and traversing mechanism including a loop having an extensible portion and an eccentric member 70 engaging said loop.

5. In a machine of the character described, the combination of a builder motion and traversing mechanism, connections between said builder motion and traversing mechanism including a loop having an extensible portion and an eccentric member 75 engaging said loop, and an arrester acting on the extensible portion of the loop during the building of a bunch to vary the traverse of 80 the traversing mechanism.

6. In a machine of the character described, the combination of a builder motion and traversing mechanism, a flexible connection between the builder motion and traversing mechanism including a loop having an extensible portion and connected to one of said parts and an eccentric member 85 embraced by the loop and connected to the other of said parts, and means for turning 90 the eccentric member to vary the traverse of the traversing mechanism during the building of a bunch.

7. In a machine of the character described, the combination of a series of spindles, a series of guides, a builder motion and traversing mechanism for moving said guides, connections between the builder motion and traversing mechanism including an elastic portion and an eccentric member, and 100 means for extending the elastic portion and turning the eccentric member during the building of a bunch.

8. In a machine of the character described, the combination of a builder motion and traversing mechanism, a connection 105 between the builder and traversing mechanism including an elastic portion and an eccentric member, an arrester connected to the elastic portion to cause the eccentric 110 member to turn and vary the traverse of the traversing mechanism during the formation of a bunch.

9. In a machine of the character described, the combination of a builder motion and traversing mechanism, a connection 115 between the builder and traversing mechanism including an elastic portion and an eccentric member, an arrester connected to the elastic portion to cause the eccentric member 120 to turn and vary the traverse of the traversing mechanism during the formation of a bunch, and means for bending the arrester to augment its action as the traversing mechanism descends.

10. In a machine of the character described, the combination of a builder motion and traverse mechanism, connections between the builder motion and traverse mechanism including a closed loop, an ec- 130

4
centric member inclosed by and engaging said loop, and means acting through said loop for turning said eccentric member on its axis during the building of a bunch and becoming automatically inoperative on the completion of the bunch.

11. In a machine of the character described, the combination of a builder motion and traverse mechanism, a flexible connection between the builder motion and traverse mechanism including a spring, an eccentric member engaging said flexible connection, and means for varying the length of said connections through the spring and eccentric member during the building of a bunch.

12. In a machine of the character described, the combination of a builder motion and traverse mechanism, connections between the builder motion and traverse mechanism including a closed loop, an eccentric member positively engaging the loop of said connection, and means for varying the length of the loop during the building of a bunch.

13. In a machine of the character described, the combination of a builder motion and traverse mechanism, connections between the builder motion and traverse mechanism including an extensible loop, an eccentric member having means for positively engaging the loop and movable about its axis to bring different portions of the ec-

centric member into positive engagement with the loop, and means acting to vary the size of the loop during the building of a bunch.

14. In a machine of the character described, the combination of a builder motion and traverse mechanism, connections between the builder motion and traverse mechanism including a loop 38 having an elastic portion, a cam member 18 having teeth for positively engaging the loop, and means acting on the loop to vary its length during the building of a bunch.

15. In a machine of the character described, the combination of a builder motion and traversing mechanism, a connection between the builder motion and traversing mechanism, comprising a sprocket chain having a loop provided with an extensible portion, an eccentrically supported member inclosed by said loop and having teeth to engage the sprocket chain, and means for acting upon the extensible portion of the loop during the building of a bunch to elongate said portion.

In testimony whereof, I have signed my name to this specification, in the presence of two subscribing witnesses.

HERBERT W. OWEN.
